(57) **CLAIM**

The ornamental design for a archery bow stabilizer, as shown and described.

DESCRIPTION

FIG. 1 is a perspective view of my new archery bow stabilizer design showing all of its parts combined as a whole;

FIG. 2 is a rotated view of FIG. 1 showing its right end mounted part detached for clarity;

FIG. 3 is a top plan view of FIG. 1, the bottom plan view is identical;

FIG. 4 is a side elevation view taken generally from the right side of FIG. 1 and looking towards the left, the opposite side is identical;

FIG. 5 is an end elevation view of FIG. 1 taken from the right end thereof;

FIG. 6 is an end elevation view taken from the left end of FIG. 1; and,

FIG. 7 is a exploded perspective view of FIG. 1 showing my archery bow stabilizer with its internal parts detached for clarity.
